UNITED STATES PATENT OFFICE.

WILLIAM S. BULL, OF GREENTOWN, INDIANA.

ATTACHMENT FOR FLOOR SURFACERS.

Application filed March 26, 1924. Serial No. 702,079.

To all whom it may concern:

Be it known that I, WILLIAM S. BULL, a citizen of the United States, residing at Greentown, in the county of Howard and 5 State of Indiana, have invented a new and useful Attachment for Floor Surfacers, of which the following is a specification.

This invention relates to floor surfacing machines and more particularly to attachments thereof.

The object of the invention is to provide an attachment for use in taking care of the dust from the edge roller of a floor surfacing machine such as that known on the market as 15 the "American universal floor surfacing machine" and which may be quickly transferred from one side of the machine to the other and connected up ready for use by unscrewing and screwing up the stop nut; 20 it being well known that the edge roller is transferable from one side to the other of the machine.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed without departing from the spirit of the invention.

In the accompanying drawings:

Figure 1 represents a side elevation of a 35 floor surfacing machine with this improved attachment shown applied to the left hand side thereof.

Fig. 2 is a top plan view of the attachment detached; and

40 Fig. 3 is a top plan or edge view of the fan housing in connection with which the attachment is used with parts broken out and in section.

The machine shown at 1 to which this 45 attachment is applied constitutes no part of the invention and hence will not be described in detail it being equipped with the usual side or edge roller 2 and with the usual fan housing 3. In the ordinary floor 50 surfacing machine a dust pan is provided for the main sanding roller not shown, and has a suction pipe 5 connected with the fan housing 3 with a discharge pipe 6 leading from said housing to the collection receptacle 7 here shown in the form of a bag secured around the discharge end of pipe 6.

This invention is designed to take care of the dirt from the side or edge sanding drum or roller 2 which is interchangeably mounted at one end or the other of the main 60 drum. The invention comprises a flexible suction pipe 10 carrying a dust pan 11 at its front end and with its other end connected with the fan housing 3 by means of a tubular arm or coupling pipe 12 which 65 extends at right angles to the coupling pipe 8 with which pipe 5 connects.

A supporting hanger 13 in the form of a metal strap is secured to the front end of the dust pan 11 and has a laterally extending 70 arm 14 at its upper end secured by a bolt 15 to a bracket 17. This bolt 15 is equipped with a wing nut 16 to facilitate the attachment and detachment of the attachment or rather of the support 13. The L-shaped 75 bracket 17 has a slot 18 at the outer end of its long arm for the passage of the bolt 15 and the short arm thereof has an open slot 19 for connection with the front part of the frame 1 as is shown in Fig. 1.

The suction pipe 10 is equipped with eyes 20 and 21 designed to be connected by links or braces 22 and 23 with the frame of the machine as is shown clearly in Figs. 1 and 2. These braces 22 and 23 are used when the 80 attachment is mounted on the left hand side of the machine and when it is employed on the right hand side suction pipe 10 is supported by a hook on the frame of the motor.

The edge roller or sanding drum 2 is transferable from one end of the machine to the other and consequently the dust collecting attachment is made transferable to operate with the edge roller in either position. The edge sanding drum 2 is made 90 slightly larger in diameter than the main drum, not shown, so that the edges of the floor may be finished without the main drum touching the floor. To use the edge sanding drum, which may be applied to either 95 end of the hollow shaft of the main drum, the rod is inserted through the drum shaft and the stub end of the edge roller forced into the drum shaft so that the pin engages in the slot at the end of the drum shaft 100 and the washer is applied to hold it in place. This edge sanding drum is a part of the "American universal floor surfacing machine" referred to and constitutes no part 105 of this invention.

The only change necessary to be made in the machine proper when applying this 110

attachment is to provide the fan housing 3 with the additional tubular coupling 12 for connection of the pipe 10 and when the pipe is not in use this coupling 12 may be closed 5 by a top 24 shown in Fig. 3.

I claim:

1. The combination with a floor surfacing machine having a fan housing and an edge sanding roll; of a flexible pipe having a 10 dust pan at one end to be positioned adjacent said roll, the other end of said pipe being detachably engaged with the fan housing, said pipe having means for mounting it on either side of the machine to adapt it 15 for connection with either end of the roller when at either end of the main drum.

2. The combination with a floor surfacing machine having a fan housing and an edge sanding roll; of a flexible pipe having a dust 20 pan at one end to be positioned adjacent said roll, the other end of said pipe being detachably engaged with the fan housing, said pipe having means for mounting it on either side of the machine to adapt it for connec-

tion with the roller when at either end of 25 the main drum, said means comprising a bracket connected at one end with the dust pan, and having a laterally extending arm at its upper end, and an L-shaped bracket having an open slot at one end for detachable connection with the machine frame.

3. An attachment for floor surfacing machines comprising a flexible pipe having a dust pan at one end and means at its other end for connection with a fan housing, 35 spaced eyes carried by said pipe, wires for engagement with said eyes and adapted to be connected with the machine frame to support the pipe intermediate its ends, a bracket rising from said dust pan carried end, and 40 another bracket detachably connected with the first mentioned bracket and having means for connection with the machine frame.

In testimony that I claim the foregoing 45 as my own, I have hereto affixed my signature.

WILLIAM S. BULL.
